UNITED STATES PATENT OFFICE.

GEORGE F. SISBOWER, OF EAST ORANGE, NEW JERSEY, ASSIGNOR TO NEW YORK COUCH BED COMPANY, OF NEW YORK, N. Y., A CORPORATION OF NEW YORK.

BED.

1,122,318.

Specification of Letters Patent. Patented Dec. 29, 1914.

Application filed February 20, 1911. Serial No. 609,710.

To all whom it may concern:

- Be it known that I, GEORGE F. SISBOWER, a citizen of the United States, residing at East Orange, in the county of Essex and 5 State of New Jersey, have invented certain new and useful Improvements in Beds, the following being a full, clear, and exact disclosure of the one form of my invention which I at present deem preferable.
- 10 For a detailed description of the present form of my invention, reference may be had to the following specification and to the accompanying drawing forming a part thereof, in which—

- 15 Figure 1 is a view of one end of my improved bed, Fig. 2 is an end elevation with the leaf in an upright position, Fig. 3 is an end elevation with leaf in a horizontal position.
- 20 My invention relates to a bed-frame having two longitudinal leaves on either side capable of being folded, one of them into either a horizontal or dropped position and the other into a horizontal, dropped or up- 25 right position. The last may be termed a three-position leaf. When both leaves are dropped a single couch or bed is formed, when both are horizontal a double bed, and when one is dropped and the other raised to 30 an upright position it forms a couch with a back.

My invention concerns the devices for securing the leaves, particularly the three-position one, in their several positions.

- 35 Referring to the drawing, A represents a bed-frame having at each end an end-bar a_1 , legs a^1 , a^2 and a brace bar a^3 . The two ends are connected by longitudinal side bars a^4 , a^5 . Along the rear edge of frame A is a 40 folding leaf B adapted to rest in either an upright position (Figs. 1 and 2) a horizontal position (Fig. 3) or a dropped position (shown in dotted lines Fig. 2) and in either position it will be securely held in 45 place. At the same time it can be shifted easily from one position to another. A curved brace D is pivoted at one end to the leaf B and at the other end passes through a slot in the leg a^1 just above the point at 50 which the side-bar a^4 is attached to the leg. At this inner end of brace D there is a notch d on its under side and also a lug d^1 loosely pivoted to the extremity of the brace. On the side bar a^4 , opposite the curved brace D 55 is a vertical flange E, forming a recess be-

tween the said flange and the side of the leg a^1 . In this recess the lug d^1 is received when the leaf B is raised to its upright position as shown in Fig. 2. Both the lug and the recess being angular the lug will not turn 60 in the recess, that is, the front and back sides of the recess come against the front and back sides of the lug d^1 so that the lug will not turn on its pivot but will afford a stop for the brace that will retain the leaf 65 in its upright position. On the other hand, as the leaf is being raised to its upright position the lug will swing freely outward on its pivot until it is dragged across the upper edge of flange E when it will swing inward 70 on its pivot and drop into the recess back of the flange. The leaf B is pivoted to the frame A by a slotted hinge connection, the slot surrounding the neck of pivot pin b . Thus, when the leaf is in its upright position, it can be lifted bodily a slight distance and so drawn away from the frame A carrying with it the brace D. This will raise the lug d^1 out of the recess, so that the leaf 75 can then be turned and lowered to dropped position, the brace D passing freely inward to the position shown in dotted lines in Fig. 2. If it is desired to have the leaf held in its horizontal position as in Fig. 3, the leaf after being lifted can be dropped when the 80 notch d comes opposite the flange E and the notch will engage the flange, as shown in Figs. 3, the leaf being thereby arrested as it is turned down to the horizontal position.

The leaf C on the front edge of frame A 90 is only intended to assume the dropped position shown in Figs. 1 and 2 or the horizontal position, and may be provided with any suitable device for securing it, such as the straight brace D^1 with a notch c that 95 will engage the lower edge of the slot in the leg a^2 . The lug c^1 will, in that case, only serve to lift the brace to free the notch by resting on the upper side of the side bar a^5 when the leaf is lifted slightly above its 100 horizontal position, thereby lifting the inner end of the brace when the leaf is subsequently lowered. This particular device is not claimed herein but forms the subject of my application No. 515,148, filed August 105 30, 1909.

What I claim as new and desire to secure by Letters Patent is:

1. A bed of the character described comprising a stationary frame, a leaf having a 110

- pivotal connection with said frame, a brace secured to said leaf, a flange carried by the stationary frame, a lug pivoted to said brace and coöperating with the latter and said flange to support said leaf in an upright position, said pivotal connection including means to permit a rectilinear movement of said leaf to disengage said lug from said flange.
- 10 2. A bed of the character described comprising a stationary frame, a leaf having a pivotal connection with said frame, a brace secured to said leaf, a flange arranged to engage said brace to support said leaf in a horizontal position, a lug pivoted to said brace and coöperating with the latter and said flange to support said leaf in an upright position, means coöperating with said flange to prevent pivotal movement of said lug when said leaf is in a vertical position, said pivotal connection including means to permit a rectilinear movement of said leaf to disengage said lug from the flange and said coöperating means.
- 15 20 25 3. A bed of the character described comprising a stationary frame, a leaf having a pivotal connection with said frame by a slotted hinge constructed to permit a rectilinear movement of said leaf, a curved brace pivoted to said leaf, a flange arranged to engage said brace to support said leaf in a horizontal position, and a lug pivoted to said brace and coöperating with the latter and said flange to support said leaf in an upright position, said lug being disengaged from said flange by a rectilinear movement of said leaf.
4. A bed of the character described comprising a stationary frame, a leaf having a pivotal connection with said frame, a brace pivoted to said leaf, a lug pivoted to said brace, means coöperating with said lug and said brace to support said leaf in an upright position, and a pivotal connection between the frame and the leaf including means to permit a rectilinear movement of the leaf to disengage said lug from the supporting means coöperating therewith.

In witness whereof I have hereunto set my hand, before two subscribing witnesses, this 17th day of February, 1911.

GEORGE F. SISBOWER.
